UNITED STATES PATENT OFFICE.

EMANUEL SMITH, OF WALLACE, IDAHO.

DRAWKNIFE.

1,376,651.

Specification of Letters Patent.

Patented May 3, 1921.

Application filed May 17, 1919, Serial No. 297,859. Renewed September 30, 1920. Serial No. 413,900.

To all whom it may concern:

Be it known that I, EMANUEL SMITH, a citizen of the United States, residing at Wallace, in the county of Shoshone and 5 State of Idaho, have invented certain new and useful Improvements in Drawknives, of which the following is a specification.

This invention relates to draw knives, and particularly to such as are provided with 10 handles pivotally connected with the shanks of the blade whereby they may be folded substantially into line with the blade for convenience in packing and transportation or for fitting in a tool chest.

15 The object of the invention is to provide a draw knife having a double edged blade equipped with reversible handles to permit the use of either blade edge, said handles being so constructed and connected with the 20 blade that a pull exerted thereon during the use of the knife will tend to hold the handles perfectly rigid in relation to the blade.

Another object is to so construct and connect the handles that when not in use they 25 may be folded down on opposite sides of the blade and operate as a guard for the cutting edges as well as to adapt the tool to be stored in a comparatively small space.

30 With the foregoing and other objects in view, which will appear as the description proceeds, the invention resides in the combination and arrangement of parts and in the details of construction hereinafter described and claimed, it being understood that changes in the precise embodiment of 35 the invention herein disclosed may be made within the scope of what is claimed without departing from the spirit of the invention.

40 In the accompanying drawings:—

Figure 1 represents a side elevation of a draw knife constructed in accordance with this invention with the handles shown in 45 full lines in operative position and in dotted lines in infolded inoperative position, arrows being employed to show the direction in which the handles are swung when changing their position.

50 Fig. 2 is an edge view of the knife, and

Fig. 3 is a transverse section taken on the line 3—3 of Fig. 1.

In the embodiment illustrated, a blade 1 is shown having differently beveled opposed 55 edges so that either one or the other may

be used at the will of the operator. Extending from the opposite ends of the blade 1 are two forgings or castings 2 and 3 which either may be made integral with the blade or attached thereto. These castings 2 and 3 have formed therein diagonally disposed slots 4 and 5 with extensions 6 and 7 at their opposite ends. These extensions 6 and 7 are arranged parallel with the blade 1 and extend in directions opposite to each other, the slot 4 being arranged at one side of the casting 2 and slot 5 at the other side of casting 3, the slot extensions forming bearings for pintles 11 of handles 8 and 9 now to be described. These 70 handles 8 and 9 are provided at their inner ends with furcations 10 which are designed to straddle the castings 2 and 3 and are connected by the pintles 11 which are designed to pass through the slots 4 and 5 75 as is shown clearly in the drawings. These castings 2 and 3 are provided at their outer ends on opposite edges with shoulders 12 and 13 which form stops for the handles when swung into opposite directions as is 80 shown clearly in Fig. 1. When the knife is to be used as shown in Fig. 1, the pintles 11 of the handles will be positioned in the extension 7 of the slot 4 and in the extension 6 of slot 5 with the handles abutting 85 against the shoulders 13 so that when force is exerted inwardly on the handles 8 and 9 the pintles 11 will move outwardly and be engaged with the extreme outer ends of the slot extensions 6 and 7 and the handles thus 90 rigidly connected with the blade.

When it is desired to use the opposed edge of the blade from that shown in Fig. 1, the handles are swung in the direction of the arrows *a* and *b* through an arc of 95 180°, and during this swinging movement the pintles 11 will pass through the diagonal slots 4 and 5 and the pintle 11 of handle 8 will be engaged with the bearing formed by the slot extension 6 while the pintle 11 100 of handle 9 will engage the bearing formed by the slot extension 7.

When it is desired to fold the handles inward to protect the cutting edges of the blade, the pintles pass through the diagonal 105 slots until they reach the inner ends thereof when they will enter the extensions 6 and 7 of the respective slots and lie in the dotted line position shown in Fig. 1, thereby protecting the edges of the blade and occupy- 110

ing a minimum amount of space. The handles shown in the drawings do not quite cover the entire length of the blade 1 and they may be made longer for this purpose if found desirable, or they may be composed of sections telescopically engaged so as to be extended when folded in to protect the blades and retracted when the knife is to be used for cutting.

10 From the foregoing description, taken in connection with the accompanying drawings, the advantages of the construction and of the method of operation will be readily apparent to those skilled in the art to which the invention appertains and while I have described the principle of operation of the invention together with the device which I now consider to be the best embodiment thereof, I desire to have it understood that 15 the device shown is merely illustrative and that such changes may be made as are within the scope of the claimed invention.

20 Having thus fully described my invention, what I claim as new and desire to secure 25 by Letters Patent, is:—

1. A knife of the class described comprising a blade, a forged end carried by said blade having a diagonally disposed slot with parallel extensions at its opposite ends extending in the same direction as the length 30 of the blade, a handle, and a pivot extending through said handle and slot and adapt-

ed to enter one or the other of said slot extensions.

2. A knife of the class described comprising a blade, a casing, forged ends carried by said blade, each having a slot with a bearing at each end thereof, said slots being diagonally disposed at opposite sides of the casing and the bearings being in the 35 form of extensions extending in opposite directions and parallel to the length of the blade, handles having bifurcated inner ends, and pintles connecting said ends and adapted to be inserted through said slots. 40

3. A knife of the class described comprising a two-edged blade having heads at its opposite ends provided with diagonally disposed slots, each of said slots having bearings at its opposite ends, handles having bifurcations at their inner ends with pintles 45 extending through said furcations, and the slots in said heads, and shoulders formed on said heads for engagement by said handles to provide for the rigid connection of the 50 handles with the blade when the knife is in use.

In testimony whereof I affix my signature in presence of two witnesses.

EMANUEL SMITH.
